UNITED STATES PATENT OFFICE.

JOHN E. GREENAWALT, OF DENVER, COLORADO.

POROUS-HEARTH FURNACE.

No. 839,064.

Specification of Letters Patent.

Patented Dec. 18, 1906.

Application filed March 27, 1905. Renewed April 24, 1906. Serial No. 313,401.

To all whom it may concern:

Be it known that I, JOHN E. GREENAWALT, a citizen of the United States, residing in the city and county of Denver and State of Colorado, have invented certain new and useful Improvements in Porous-Hearth Furnaces; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to improvements in porous-hearth furnaces of the general class set forth in my application for United States patent filed December 27, 1901, Serial No. 87,510. In my present invention the hearth 20 proper is similar in construction to that illustrated and described in my aforesaid application.

25 My improvements consist in providing means for passing air or gas from the furnace-chamber down through the bed of ore and through the porous hearth into chambers or compartments formed underneath the hearth, whereby the volatilized values contained in the fumes or gases may be 30 saved.

35 The invention further embraces, in addition to the porous hearth and means for passing air or other gas or fumes downwardly through the bed of material and the hearth upon which it rests, means for precipitating the values contained in the said fumes or gases.

40 The invention further embraces the introduction of air or other gas through the top of the furnace into the chamber thereof above the bed of ore or other material lying upon the hearth, the said air or gas being introduced at some distance from the ordinary source of heat or producer-gas delivered to 45 the furnace for combustion purposes. This air introduced to the top of the furnace is delivered thereto through a number of nozzles or conduits, whereby it is properly distributed and caused to mingle with the fuel- 50 gases, resulting in the production in an economical manner of the necessary heat for the purpose of roasting or otherwise properly treating the ore or other material placed upon the porous bed.

55 In this specification the mechanism will be described with special reference to its use in

roasting or oxidizing ores and the saving of the volatilized precious metal values contained in the fumes within the furnace.

There are certain ores carrying the precious metals in such combinations that when the ore is roasted a considerable percentage of the gold and silver volatilizes in the form of fumes, and in the ordinary furnace these valuable fumes mix with the products of combustion and dust of the furnace and pass into dust-chambers and the furnace-stack. Experience has shown that it is a difficult matter to completely precipitate and recover these values after they are mixed or mingled 60 with the large volume of fuel-gases and dust arising from the ore or other material under treatment. In my invention by reason of a downward suction through the hearth these fumes are drawn downwardly through the 65 hearth and deposited in a condensing-chamber in a comparatively pure state. By this arrangement the valuable constituents of the gases are concentrated in a small current as compared with the total volume of gases 70 from the furnace proper.

Having briefly outlined my improved construction, as well as the function it is intended to perform, I will proceed to describe the same in detail, reference being made to 75 the accompanying drawings, in which is illustrated an embodiment thereof.

In the drawings, Figure 1 is a cross-section of the furnace, the condensing-chamber being shown in vertical section. Fig. 2 is a top 80 plan view of the furnace, shown on a smaller scale, the flues for the introduction of the heat or fuel-gases at one end of the furnace and for the escape of the waste gases at the opposite extremity of the furnace being 85 shown in horizontal section. Fig. 3 is a central longitudinal section taken through the furnace on the same scale as Fig. 2.

The same reference characters indicate the same parts in all the views.

When ore is roasted upon a porous bed of the character illustrated in the drawings, rabbelling mechanism is necessary for the purpose of stirring the ore and advancing it longitudinally on the hearth, whereby new surfaces 100 of the ore are constantly exposed to the action of the heat. In the furnace illustrated in the drawings I contemplate the use of rabbelling mechanism, as will be readily observed from an inspection thereof. The rabbles 105 themselves, however, are not illustrated; but it must be understood that their employ-

ment will be required. To this end I have shown sprocket-wheels 20 at each end of the furnace, which the endless rabble-chains (not shown) would engage in actual practice. In 5 the drawings the ore to be roasted or treated is supposed to be placed upon the porous bed 1. This bed constitutes the hearth of the furnace, and the ore is rabbled over this hearth by suitable mechanical rabbles, (not 10 shown,) but heretofore briefly described. The furnace is preferably heated by means of producer-gas introduced through the flue 2 and is supplied at intervals with air through a series of pipes 3, having nozzles passing 15 through the top of the furnace, enough pipes and nozzles being employed to give the desired or necessary distribution, the air being supplied to the pipes 3 from a main pipe 13, connected with any suitable source of air- 20 supply. The air so introduced mingles with the producer-gas, furnishing the necessary heat for the roasting operation, and the waste gases pass through the flue 4 to the chimney or stack. Directly underneath the 25 porous hearth or bed are large chambers *a* and *b*, which are divided by suitable cross-walls into compartments, so that the volume of gases drawn through the hearth may be controlled and regulated in the different 30 compartments. The hearth is constructed upon a series of arches in the form of solid rings 5, having spaces *C* of about four inches in width between them. These spaces are covered by a course of bricks *H*, set on edge 35 and about one inch apart, leaving intermediate spaces *E* communicating with the spaces *C* between the arches 5. Upon these bricks is placed a layer of coarse gravel or ore *F* and then a layer of smaller pieces until the last 40 four inches, which consist of sand or fine ore.

The gases are drawn through the ore-bed and the porous hearth into the chambers *a* and *b* and thence through pipes 7 into condensing-chambers 8 by the suction created 45 by means of a steam-jet pipe 9 entering each pipe 7 or other suitable suction-producing apparatus. Each chamber 8 is provided with a number of condensing-compartments 21, formed in its lower portion, while its upper portion is filled with brick checker-work 50 22, constructed substantially as shown in the drawings, whereby the fumes may pass upwardly therethrough and the condensing-water flow downwardly to the reservoirs 19 in the bottom of each chamber, the said reservoirs being supplied by the water from the 55 perforated pipes 10, mounted in the top of the condensing-chamber. The condensed or precipitated values may be easily recovered 60 from the reservoirs 19.

The waste or unconsumed gases pass from each condensing-chamber through a pipe 23 into a main conduit 24, (see Fig. 2,) which leads to a suitable stack. (Not shown.) As 65 shown in the drawings, referring to Fig. 2,

each condensing-chamber is provided with a number of branch water-pipes 10, connected with a main pipe 25, leading from any suitable source of supply. The supply of water to each pipe 10 is controlled by a valve 26.

Assuming that rabbles are employed for stirring the ore treated upon the porous hearth 1, the rabbles or stirring devices act on the ore between the sides 27 of the hearth, while the endless chains carrying the rabbles 75 rest upon tracks 28, located outside of the parts 27. Mounted on top of the furnace are tracks 29 for the support of the rabble-chains as they travel above the furnace. These tracks 29 are in vertical alinement with the 80 tracks 28 within the furnace.

By incorporating a suitable catalytic agent—as platinized asbestos, ferric oxid, &c.—in the porous bed a considerable proportion of the sulfurous anhydrid contained 85 in the ore-fumes may be cheaply and economically converted into sulfuric anhydrid, and thus into sulfuric acid in the condensing chamber or chambers.

Having thus described my invention, what 90 I claim is—

1. In a furnace for treating ore or other material, the combination of a porous bed or hearth, and means for passing air or gas downwardly through the material and the 95 hearth upon which it rests.

2. In a furnace of the class described, the combination of a porous hearth and means for passing air or gas from within the furnace downwardly through the porous hearth, and 100 means for condensing valuable volatilized elements carried downwardly with the gas.

3. In a furnace, the combination of a porous hearth having incorporated therein a catalytic agent, means for passing air or furnace-gases downwardly through the ore and 105 through the porous hearth or bed.

4. In a roasting-furnace, the combination of a porous hearth having incorporated in it a catalytic agent, means for passing air or furnace-gases downwardly through the ore and through the porous hearth, and means for condensing the volatilized values carried by the fumes or gases, substantially as described.

5. In an apparatus of the class described, the combination of a roasting-furnace provided with a porous hearth, a chamber located beneath the porous hearth, and means for passing air or other gases from the furnace downwardly through the hearth into the said chamber.

6. In an apparatus of the class described, the combination of a furnace provided with a porous hearth, a chamber located beneath the porous hearth and composed of a number of intercommunicating compartments, means for passing air, gases or furnace-fumes downwardly through the hearth into the chamber from beneath, and a condensing-chamber 125 130

connected with the chamber beneath the hearth.

7. In an apparatus of the class described, the combination of a furnace provided with a porous hearth, a chamber beneath the furnace, means for passing air, gases or fumes from the furnace downwardly through the hearth into the chamber below the same, a condensing-chamber communicating with the chamber beneath the hearth, and means for supplying the condensing-chamber with the necessary water for condensing purposes.

8. In a roasting-furnace, the combination

of a porous hearth, means for passing air in distributed volume through the top of the furnace into the roasting-chamber, and means for passing air, gases or furnace-fumes downwardly through the porous hearth for the purpose set forth.

In testimony whereof I affix my signature in presence of two witnesses.

JOHN E. GREENAWALT.
